UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 14,803, dated February 19, 1884.

Application filed November 19, 1883. Term of patent 3½ years.

To all whom it may concern:

Be it known that I, LOUISE TULLY, of the city, county, and State of New York, have invented and produced a new and original Design for a Pattern of a Miss's Costume, numbered 8,967; and I do hereby declare that the engraved prints accompanying this specification convey to any one accustomed to using paper patterns a clear understanding of how a garment made up by the pattern will appear.

The design unites a Princess dress that exhibits closely-fitted fronts buttoning from the neck to a little below the waist-line, and a closely-fitted back, a deep front drapery that displays draping plaits at each side, with a revers below the plaits in the left side, where the drapery falls in a point, and a deep full back drapery that exhibits plaits at the top, an opening for some distance through the lower part of the center, and loopings at the sides and center, each side, as it descends, being rounded away to assume a pointed outline at the bottom of the opening. A standing collar, a deep round collar, and coat-sleeves are added.

What I claim as my invention, and desire to secure by Letters Patent, is—

The design for a miss's costume, as shown in the engraved prints accompanying this specification.

LOUISE TULLY.
